ATTORNEYS

UNITED STATES PATENT OFFICE.

BURR A. BROWN, OF ALBERT LEA, MINNESOTA.

BILL FOLD.

Application filed November 16, 1923. Serial No. 675,189.

To all whom it may concern:

Be it known that I, BURR A. BROWN, a citizen of the United States, and resident of Albert Lea, in the county of Freeborn, in the State of Minnesota, have invented certain new and useful Improvements in Bill Folds, of which the following is a specification.

My invention relates to improvements in bill folds and it consists of the constructions, combinations, and arrangements herein described and claimed.

An object of the invention is to provide a bill fold or currency pocket-book by means of which currency may be held in a more compact and advantageous manner.

Another object of the invention is to provide a bill fold which is arranged to receive and hold a plurality of bills, each independently of the other, so that one bill may be extracted without handling or disturbing any other bill.

A further object of the invention is to provide a bill fold having a flexible comb between the teeth of which the bills are independently held, said comb being flexed into a kind of fan-shape when it is desired to insert the bills in the first instance.

Other objects and advantages will appear from the following specification, reference being had to the accompanying drawings, in which,

Figure 1 is a perspective view showing the bill-fold closed.

Figure 2 is a perspective view showing the bill-fold opened.

Figure 3 is a perspective view showing how the comb is flexed in putting the bills in place.

Figure 4 is a perspective view showing how the bill-fold is held when paging through the various bills in order to find one of the desired denomination.

In carrying out the invention provision is made of a single piece of material such as leather, imitation leather, heavy binders' cloth or the like, this piece of leather being indicated 1, 2 and 3 respectively, indicating the back of the bill-fold, the inner flap and

the outer flap. The inner and outer flaps carry the component parts 4 and 5 of an ordinary snap fastener which is commonly seen on gloves.

One side of the back 1 is a little larger than the other, that is to say, the leather along the left side is cut so as to produce

a flange 6 which is lapped over the base or back 7 of a comb. The comb has a plurality of teeth 8, the end teeth 9 and 10 being considerably wider than those in the middle for the purpose of rigidifying the back 1 transversely. The back 7 of the comb is sufficiently heavy to serve this purpose lengthwise of the bill-fold. The comb is either cemented, eyeleted or riveted in place along the back 7 and the tooth 10. Any one may be used according to the nature of the outside material used.

The teeth 8 of the comb are readily flexed. The back 7 of the comb may also be flexed, that is to say, it may be bent or twisted when it is desired to insert the currency in the spaces between the teeth. The fact that the back of the comb rigidifies the bill-fold longitudinally is not to be understood to mean that the comb back is so stiff that it cannot bend. The comb is made of celluloid or other suitable material, and is adapted to serve both purposes very well.

All of the teeth are straight as clearly shown in Figure 2. The large end tooth 9 becomes useful in permitting the user to obtain a hold on the comb with the thumb of the left hand (Fig. 3) when he desires to flex or twist the comb in inserting the currency in the first instance. The inner flap 2 is cut away on a bias as at 11. The purpose in thus cutting the flap 2 away is to make it possible to have access to the currency in turning down the exposed corners of the bill in searching for one of the wanted denomination.

The operation may be readily understood from the foregoing description. Assume that the user of the bill-fold desires to fill it with a plurality of bills. He holds the bill-fold in the fingers of the left hand about as shown in Figure 3. The end tooth 9 is gripped by the thumb and the teeth 8 of the comb are spread in a fan-like manner so that the spaces may be opened and the currency inserted in an orderly way. The bill-fold may then be folded up and snapped in the closed position as shown in Figure 1.

In holding the bill-fold in the left hand as stated the back 7 of the comb will be bowed to a slight extent. This bowing of the comb is not prevented by the fact that the back of the comb rigidifies the bill-fold longitudinally. The material of which the comb is made is intended to be such that both functions may be performed. The

bills or currency may either be folded before insertion or inserted without folding, this depending of course on the size of the bill-fold.

5 When it is desired to use a bill, the bill-fold is again held in the left hand, the outer flap 3 being thrown all the way back (Figure 4), the inner flap 2 being held down with the thumb of the left hand. The inter-
10 posed flap 2 obviates the necessity of pressing down on the teeth of the comb itself. The corners of the bills exposed beyond the cut away biased portion 11 of the inner flap 2 may now be turned down with the fingers
15 of the right hand until the bill of the wanted denomination is found. This bill may be extracted without in any way molesting the other bills. It is not necessary to handle any of the other bills in order to
20 reach and extract a particular one, other than to page through said bills as just explained.

The advantages of the improved bill-fold are obvious enough. The bills will be held
25 firmly in position after having been once inserted. The natural resiliency of the comb and the snapped inner and outer flaps will contribute largely toward the holding of the bills. Again, all of the bills will abut the
30 closed side or back 7 of the comb. It is therefore possible that they may slip one way only, but from this they will be prevented by the means already described.

Ordinarily, bills are placed in large sized
35 bill-folds in a spread open position without regard to order, and afterwards folded up to a convenient size to fit a pocket in the users' clothing. In these bill-folds, the bills are not quickly and easily accessible and
40 extracted, and generally require the taking out of some of the bills, in order that they may be looked over, and the selection of a particular bill made.

With the improved bill-fold this is not necessary. The bills are preferably folded once each way to reduce them to one-quarter size before insertion between the teeth of the comb. This calls for a comparatively small bill-fold which is readily pocketed. It is to be understood that the bill-fold may be made of any flexible material, some of which have already been mentioned above, while the comb may be made of materials of different values such as celluloid, ivory, horn (imitation or otherwise), or possibly 55 silver, gold or the like.

One purpose is to devise a bill-fold that can be manufactured very cheaply in the event that it is to be used as an advertising specialty. Again, other bill-folds may be made up of expensive leather, and in such cases the comb will be made of a corresponding high grade of material. The appearance of the bill-fold will be much enhanced by suitably applying a silver or gold plate to 60 the outside flaps on which the name or monogram of the owner may be engraved.

While the construction and arrangement of the improved bill-fold as herein described and claimed is that of a generally 70 preferred form, obviously modifications and changes may be made without departing from the spirit of the invention or the scope of the claim.

I claim:—

75 A bill-fold comprising a case, a comb of resilient material including a back and a plurality of teeth affixed to the case along said back, a broad tooth at one extremity of the comb also fastened to the case, and a similar broad tooth at the other end of the comb adapted to be gripped by the thumb of one hand to twist the comb to facilitate insertion of folded currency.

BURR A. BROWN.
